(57) **CLAIM**

The ornamental design for a lunch box, as shown and described.

DESCRIPTION

FIG. 1 is a front perspective view of a lunch box showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another front perspective view thereof with an additional lunch box.

The broken line portions of the lunch box in FIGS. 1-9 represent unclaimed portions of the claimed design and form no part thereof. The broken lines of the additional lunch box in FIG. 9 illustrate unclaimed environment and forms no part of the claimed design.

1 Claim, 7 Drawing Sheets
